UNITED STATES PATENT OFFICE.

LOUIS BELL, OF NEWTON, MASSACHUSETTS, ASSIGNOR, BY MESNE ASSIGNMENTS, TO THE BELL HOUSE COOLING COMPANY, OF NEW YORK, N. Y.

COOLING APPARATUS.

SPECIFICATION forming part of Letters Patent No. 636,886, dated November 14, 1899.

Application filed January 28, 1898. Serial No. 668,248. (No model.)

To all whom it may concern:

Be it known that I, LOUIS BELL, a citizen of the United States, residing at Newton, county of Middlesex, and State of Massachusetts, have 5 invented certain new and useful Improvements in Cooling Apparatus, of which the following is a specification, reference being made to the accompanying drawings, wherein—

Figure 1 is a vertical section, partly in elevation. Fig. 2 is a horizontal section on the line $x x$ of Fig. 1. Fig. 3 is a horizontal section on the line $y y$ of Fig. 1 with certain parts in elevation. Fig. 4 shows the mantle in detail. Fig. 5 is a horizontal section of the parallel ducts on a larger scale, and Fig. 6 is a vertical section of my drying apparatus.

My apparatus is based on the principle of abstracting heat from a current of air by evaporating in immediate proximity thereto a liquid, preferably water, by means of a second current of air. Various cooling devices based on this principle have been proposed, from which mine differs in many important respects. First, in order to attain a practicable device it becomes necessary to separate the evaporating-chamber from the one containing the air to be cooled in order that the air delivered to the apartment may remain dry enough for use, and to accomplish this separation with even approximate economy and capacity I have found it necessary to provide two ducts, through which the respective currents are passed, separated by a wall of a novel character. Thus instead of a separating-wall of earthenware, iron, or ducts of metal, such as might be capable of sustaining a stream of liquid or unbalanced air-pressure, I use an extremely thin film of copper, with suitable devices for maintaining its shape and protecting the same against deformation by mechanical strain and pressure and against galvanic corrosion. I have used with success a film four-thousandths (.004) of an inch in thickness, which will afford an approximate conception of the nature of the film. By the term "film" as used in this specification I mean a wall thinner than the sheet-metal walls heretofore used in this art, as hereinbefore elucidated. Instead of copper aluminum might be used, but with less favor-

able results. I arrange the ducts separated by this film in a novel manner and provide on the evaporating side a distributing-mantle of a peculiar character, as will be herein-after described. This mantle will be kept 55 moistened with water by devices which I have invented, and the evaporation of such moisture by the air-current will produce a cooling effect that will abstract the heat from the air-current on the other side of the wall. The 60 reason for the inefficiency of various other structures and the success of the one I have produced seems to be, so far as the character of the wall is concerned, in the fact that the evaporation of water by an air-current produces such a comparatively low difference of 65 temperature between the opposite sides of the wall at any given point that no practicable amount of heat can be conducted through the wall unless composed of such a 70 film as I have provided. Moreover, the chilling effect of the evaporation should take place on the surface of the film in the closest possible proximity to the air in the cooling-chamber, so that the resistance of heat conduction to said air shall be as small as possible with relation to the resistance through the layer of moisture to the evaporating-blast. In this way the percentage of cooling 75 energy absorbed by said air in the cooling chamber or duct is large in relation to the percentage absorbed by the water and by the air in the evaporating-chamber. By reason of the feature just mentioned and those to be 80 herein-after described I have succeeded in securing a discharge of a cubic foot of air per second at a temperature of 65° with an expenditure of two hundred watts of power, this 85 temperature being nearly independent of the initial temperature. I provide, moreover, an 90 arrangement whereby the cooling energy absorbed by the unevaporated water may be almost entirely recovered and the efficiency of the apparatus largely increased thereby. I have also provided arrangements for adjusting and regulating the admission of water to the evaporating-chamber and distributing it 95 properly over the surface of the separating-wall. I have also devised means for adjusting the volume of one or both of the air-currents 100

to correspond to the degree of saturation of the evaporating air, of which the evaporating efficiency is dependent upon its degree of humidity. I have also devised various details 5 essential to a structure capable of practical service, including an arrangement for insulating electrically the copper film to protect it against galvanic corrosion, and a drying apparatus, which may be used in certain cases 10 when the cooled air is so damp that its temperature brings it nearly to the dew-point, which would result in the depositing of moisture in the cooled apartment.

Referring to Fig. 1, A represents an inclosing box of wood or of iron, and B an insulating-lining therefor, made, preferably, of rubber or similar yielding material. This box is divided by a series of partitions C C into a 15 long sinuous passage, duct, or tube having six vertical lengths connected into a continuous series by curved joining sections C² at the ends. A space is left above and below the walls of this passage, wherein are placed small tanks D and E. Within the passage just mentioned and centrally therewith is extended a 20 parallel tube, constituting the cooling duct or chamber, through which the current of air to be cooled is passed, and having a peculiar construction, which may be described as follows:

Referring to Fig. 5, which shows a transverse section of the tube, A' is the removable front cover, and A is the wall of the inclosing box. F is one of three braces (see also 25 Fig. 1) which are made of copper and extend across the box, being let into, so as to be flush with the surface of the edge of walls A and attached thereto by screws. G' G' are strong channel-shaped copper strips forming the opposite ends of the rectangular tube G and shaped to conform to the curvature of the tube at the several turns or folds. Between these two channel-bars are stretched the copper films G² G², which are brazed or riveted 30 thereto, so as to be stiffened and maintained thereby and form a duct having the described film-wall. At intervals wooden or metal blocks H H are set into the channel-bars, and a bolt K is extended between them to hold 35 them firmly apart. Any other expedient by which the thin wall of copper may be mechanically stiffened can be employed. The strips F F are insulated from the sheet-iron walls C, as shown in Fig. 5, or they may be insulated from the strips G' by suitable sheets and washers of rubber, so that no galvanic corrosion of the film can take place. The film must 40 also be composed of non-corrodible material, since a substance like iron if made so thin would be rapidly destroyed. The outer surface of this tube G is provided with a removable mantle for distributing the moisture over its entire extent. Ordinary cloth or felt is not feasible for this purpose, being an effective heat insulator and containing foreign substances, which form more or less of a sedi-

ment that clogs up the passages, particularly the small drip-tubes hereinafter referred to, and prevents the due spread of the moisture. I employ for this purpose a very fine meshed 70 netting, made of unsized cotton or linen, which is cut in strips, with strengthening-bands at the edges, and then laid over the tube and laced or otherwise fastened thereto, so as to be readily detachable, as appears in Fig. 4 75 at L. For moistening this mantle I provide at each of the three upper bends in tube G four pipes J J J' J', the first two being located directly above the tube G and the other two just inside the bend, all of them being 80 closely adjacent to the tube. These tubes are provided with removable nozzles I, through which passes a small central perforation, so that the water will issue therefrom in drops or a small stream and be projected onto the 85 absorbing-mantle, which will distribute it uniformly over the surface of tube G. The flow of the liquid being longitudinally with the tube G, a comparatively short length of drip-tube is required and the nozzles may be 90 fewer and larger than if the flow were transverse to the tube.

The excess of moisture will be collected at the lower bend of the sinuous containing-passage, where it will drop through a small perforation n into the tank E. The water is supplied to the pipes J J J' J' from cross-pipes M, set into a removable section of cover A', the drip-pipes being all connected thereto. The tube M will be connected with the bottom of tank D by two joints of pipe M' and M², so that the drip-tubes, with the removable cover, can be drawn forward at any time, as one would open a drawer, and the tubes examined, as best shown in Fig. 3.

N is a blower driven by any suitable motor, such as an electric motor O, and the blast therefrom is delivered into the lower left-hand end of the sinuous evaporating-passage, in which is contained the cooling-tube G. A 100 damper S is placed in the evaporating-passage and another damper S' in tube G, so that the volume of air in both can be adjusted. The air-blast divides, part entering the tube G and the other part passing outside of the 105 tube throughout the entire length of the passage. The air external to the tube will evaporate the moisture contained in the mantle, and thus produce a cooling effect, which, as already described, is largely taken up by the 110 air in the tube. The latter is conveyed after it leaves the apparatus to the apartment to be cooled, while the evaporating air emerges 115 saturated with moisture and is conducted to the sewer or some place outside of the building. 120

The surplus moisture is collected, as described, in the tank E, which, it should be observed, is contained within the apparatus inside of the heat-retaining wall, so that it shall retain the same temperature as the evaporating-blast. The same is true of tank D. In order that the cooling effect absorbed by 125

the water may not be lost, I provide that the same water shall be used again and again, it becoming cooler each time it is passed over the mantle, until an equilibrium is restored 5 between its cooling tendency and the heating tendency of the evaporating stream of warm air. For this purpose I provide a pump P, which shall act automatically at intervals to draw the water E and deliver it to the tank 10 D, whence it is again passed over the mantle in the manner already described. The float V in the lower tank is arranged so that when it reaches a predetermined level it will operate clutch W through the arm n' and swing- 15 ing lever n², as clearly illustrated in Figs. 1 and 2, to connect the pump P to the shaft of the motor O and blower N. When the motor is in operation, the electromagnet Y' is energized, thereby attracting one end of the 20 stop-cock, and when the motor ceases to operate the current is cut off from the magnet and the weight T' returns the stop-cock to its closed position, all as will be readily understood. This will set the pump in operation 25 and elevate the water into the upper tank until the water in E is at a predetermined low level, when it will throw the clutch again out of engagement and stop the pump. The waste by evaporation is supplied to the lower 30 tank E by a drip-pipe T, in which a cock X is turned sufficiently to allow approximately the proper amount of water to enter the tank. This cock X may be controlled by a magnet Y in the circuit of the motor and opened only 35 when the motor is in operation.

In order that the volume of the evaporating-current may be in direct ratio to its humidity, I may provide in the outlet-pipe of blower N, where it will be subjected to the incoming 40 air, a compound temperature-strip, (shown at X² in dotted lines, Fig. 1.) This strip may be kept moistened by a wick X³ dipping into tank E. The strip will expand or contract, according to the temperature of evaporation 45 occasioned by the incoming air-current, being higher as the air is drier. This strip is connected to a cord P², which passes over a pulley on the shaft of damper S, and may also be connected, if desired, with damper S', but 50 so as to act oppositely thereon. A second pulley with a counterbalancing-weight will also be applied to the damper-shaft. By this means the volume of the evaporating-blast will be adjusted with relation to the volume 55 of air to be cooled according to the degree of saturation of the former.

In Fig. 6 I have shown a drier that in some cases may be introduced into the stream of cooled air after it leaves the cooling apparatus and before it is delivered to the apartment. This drier consists of a box A², connected on one side to the above-described tube G and on the other side to an outgoing tube G⁴, leading to the apartment, such connection being effected by any of the usual and well-known pipe connections, not necessary to illustrate. Within this box are a se-

ries of trays t, readily removable and provided with lips on alternate sides, which engage with interior ribs t' on the box and so 70 form a sinuous passage for the air as it passes through the box from the inlet to the outlet pipe. In each of these trays is contained a layer of anhydrous copper sulfate, which will absorb a sufficient amount of moisture to 75 prevent in any case a deposition of water from the cooled air. The trays will be removed when the drying material becomes saturated and turns blue. They will then be placed in an oven or otherwise heated for a short time, 80 when the moisture will be evaporated and the material again turns white. This can be repeated indefinitely at the required intervals whenever it is necessary to use the apparatus in a damp climate. 85

What I claim as new, and desire to secure by Letters Patent, is—

1. An air-cooling apparatus, comprising, in combination, two parallel ducts traversed by distinct air-currents and separated by a wall 90 consisting of a mechanically-stiffened film of non-corrodible material, provided on one side with an absorbent mantle, together with means for moistening the said mantle, substantially as described. 95

2. An air-cooling apparatus, comprising, in combination, two parallel ducts traversed by distinct air-currents and separated by a wall consisting of a mechanically-stiffened film of non-corrodible material, an absorbent mantle on one side of said wall, means for moistening said mantle, and means for delivering air into the said ducts under substantially the same pressure whereby the said wall is relieved of unbalanced pressure on its opposite 105 sides, substantially as described.

3. An air-cooling apparatus, comprising, in combination, two parallel ducts traversed by distinct air-currents and provided with a separating wall consisting of a metal film covered on one side with a detachable absorbent mantle, consisting of a fine-meshed netting of unsized textile material, together with means for moistening the said mantle, substantially as described. 110

4. An air-cooling apparatus, comprising, in combination, two parallel ducts made in straight sections, connected by curved end pieces into continuous sinuous passages and separated by a metallic film, in suitably-supported sheets, covered on one side with an absorbent mantle, together with means for moistening the said mantle, substantially as described. 115

5. An air-cooling apparatus, comprising, in 125 combination, two parallel ducts traversed by separate air-currents, the said ducts being made in vertical sections, connected by curved end pieces into continuous sinuous passages and provided with a separating- 130 wall composed of a metallic film, an absorbent mantle on one side of said wall and means for moistening the said mantle, consisting of a pipe provided with one or more nozzles at

the top of each one of the respective sections, the said nozzles being adapted to deliver the water to the mantle in such manner that it may flow longitudinally with the direction of 5 the ducts, substantially as described.

6. An air-cooling apparatus, comprising, in combination, two parallel ducts traversed by distinct air-currents and separated by a wall, consisting of a metallic film, the said ducts 10 being made in vertical sections, connected at their ends by curved pieces joining them into sinuous ducts, an absorbent mantle attached to the said wall and means for moistening the said mantle, consisting of pipes provided with 15 nozzles at the upper ends of the respective sections, said nozzles being placed on both sides of the duct through which passes the air to be cooled, substantially as described.

7. In an air-cooling apparatus, the combination 20 of an inclosing casing, a series of dividing-walls C C connected alternately at their upper and lower ends to form a sinuous evaporating-duct, of a parallel air-duct placed centrally in the said evaporating-duct and provided with opposite walls consisting of metal 25 films, a detachable absorbent mantle on each of the said walls and means for moistening the said mantle, consisting of a pipe with nozzles at the top of each section of cooling-tube 30 and on both sides of said tube for delivering water to both of the said mantle-covered walls, substantially as described.

8. In an air-cooling apparatus, the combination 35 with an inclosing casing of dividing-walls therein, connected at their opposite ends alternately, so as to form a continuous passage, an air-duct with thin metallic walls contained in and parallel with the said evaporating-duct, an absorbent mantle on the walls of said air-duct, means for moistening said mantle and a drip-tank below the said evaporating-duct, the latter being provided at the bottom of each 40 section with an opening through which the surplus water is delivered into the said tank, substantially as described.

9. In a cooling apparatus, the combination 45 with an inclosing casing, of two parallel ducts, separated by a film of metal, one receiving an evaporating-current and the other a current 50 of air to be cooled, an absorbent mantle on said film, means for delivering water to the said mantle and a drip-tank below the said ducts, having an unperforated bottom, whereby the surplus moisture from the mantle may be allowed to accumulate and the cooling energy absorbed thereby retained, substantially as described.

10. In a cooling apparatus, the combination 55 with a suitable casing, of two parallel ducts 60 separated by a film or membrane, one receiving an evaporating-current and the other a current of air to be cooled, an absorbent mantle on the evaporating side of said film or membrane, a tank containing a body of water, a supply-pipe adjusted to deliver water to the apparatus and means to govern the supply of water at a rate commensurate with the

evaporation, and means for delivering the water from said tank to the absorbent mantle, whereby a surplus body of cooled water 70 may be maintained in the apparatus to which the evaporating process is applied, substantially as described.

11. In a cooling apparatus, the combination 75 with a suitable casing, of two parallel ducts, separated by a film or membrane, one receiving an evaporating-current and the other a current of air to be cooled, an absorbent mantle on the said film or membrane, a tank receiving the surplus water from said mantle 80 and a supply-pipe for delivering fresh water to the said surplus water in the tank and means to govern the supply of fresh water to an amount commensurate with the evaporation; whereby the fresh water is subjected to 85 the cooling effect of the surplus water before it is itself passed over the mantle, substantially as described.

12. In a cooling apparatus, the combination 90 with a suitable casing, of two parallel ducts, separated by a film or membrane, one receiving an evaporating-current and the other a current of air to be cooled, an absorbent mantle on the evaporating side of said film or membrane, means for moistening said mantle, an operating-motor for delivering the air to said ducts, a supply-pipe for delivering water to said apparatus to make up for the evaporated water and a stop-cock in said supply-pipe, controlled by the operation of said motor, whereby the water is supplied only while the apparatus is at work, substantially as described. 100

13. In a cooling apparatus, the combination 105 with a suitable casing, of two parallel ducts, separated by a film of metal, one receiving an evaporating-current and the other a current of air to be cooled, an absorbent mantle on the evaporating side of said film, two tanks in said casing, one above and the other below the ducts aforesaid, a connection from the upper tank for delivering water therein to the said mantle, and a pump for returning the water from the lower tank to the upper one, substantially as described. 115

14. In a cooling apparatus, the combination 120 with a suitable casing, of two parallel ducts, separated by a film of metal, one receiving an evaporating-current and the other a current of air to be cooled, an absorbent mantle on the evaporating side of said film, two tanks in said casing, one above and the other below the ducts aforesaid, a connection from the upper tank for delivering water therein to the said mantles, a pump for returning the water from the lower tank to the upper one, and a supply-pipe delivering to the lower tank an amount of water sufficient to make up for that lost by evaporation, substantially as described. 125

15. In a cooling apparatus, the combination 130 with a suitable casing, of two parallel ducts, separated by a thin metallic wall, one receiving an evaporating-current and the other a

current of air to be cooled, an absorbent mantle on said wall, means for delivering water to the said mantle, a drip-tank below the said ducts for receiving surplus water from the 5 mantle, a float controlled by the said surplus water and a pump controlled by said float for delivering the surplus water to the top of the mantle, substantially as described.

16. In a cooling apparatus, the combination 10 with a suitable casing, of two parallel ducts, separated by a film or membrane, one receiving an evaporating-current, the other a current of air to be cooled, an absorbent mantle on the evaporating side of said film or membrane, a drip-tank for receiving the surplus water from the mantle, a pump for returning the water to the top of the mantle, an operating-motor for delivering the air-current, and means for periodically connecting the said 15 pump to the said motor for returning the drip-water to the mantle, substantially as described.

17. In a cooling apparatus, the combination 20 with a suitable casing, of two parallel sinuous ducts, separated by a film of metal, one receiving an evaporating-current and the other a current of air to be cooled and each section of the evaporating-duct communicating with a drip-tank below the two ducts and exterior 25 thereto, an absorbent mantle on the evaporating side of said film, a supply-pipe for delivering water to the apparatus to make up for the evaporated water, and means for returning the water in said tank to the top of 30 the mantle, substantially as described.

18. In a cooling apparatus, the combination 35 with an evaporating-duct, of a parallel cooling-duct provided with strengthening-ribs between which is extended a film of non-corrodible metal serving as a separating-wall between the two ducts, an absorbent mantle on the evaporating side of said wall and means for moistening the said mantle, substantially as described.

40 19. In a cooling apparatus, the combination 45 with an evaporating-duct, of a parallel cooling-duct provided with longitudinal strengthening-ribs between which is extended a film of non-corrodible metal serving as a separating-wall between the two ducts, an absorbent mantle on the evaporating side of said wall

and means for moistening the said mantle, substantially as described.

20. In a cooling apparatus, the combination 50 with a cooling-tube having a suitably-supported wall consisting of a film of non-corrodible material, of a detachable mantle for said wall, consisting of a layer of fine-meshed netting and connecting devices for attaching the said mantle to the wall, substantially as 55 described.

21. In a cooling apparatus, the combination 60 with an air-duct having a wall consisting of a suitably-supported film of non-corrodible metal, of a detachable absorbent mantle, said 65 mantle consisting of a layer of fine-meshed netting, provided with attaching devices for applying the mantle to the wall, substantially as described.

22. In a cooling apparatus, the combination 70 with two parallel ducts separated by a wall composed of a suitably-strengthened film of metal and covered with an absorbent mantle, of means for moistening the said mantle, consisting of a movable pipe provided with a series of nozzles at the top of the mantle, and a suitable casing provided with a covered opening adjacent to the said tube, substantially as described.

23. In a cooling apparatus, the combination 75 with two parallel ducts, separated by a thin metallic wall, one containing an evaporating-current and the other a current of air to be cooled, of a hygrometrically-controlled regulator for the air-currents, for adjusting the 80 volume of the evaporating-current relatively to the current to be cooled, in accordance with the humidity of the said evaporating-current, substantially as described.

24. In a cooling apparatus, the combination 85 with an evaporating-duct, of an adjacent air-duct separated from the evaporating-duct by a metallic film suitably supported and insulated electrically, substantially as described.

In witness whereof I have hereunto set my 90 hand, before two subscribing witnesses, this 95 26th day of January, 1898.

LOUIS BELL.
